UNITED STATES PATENT OFFICE.

PIETRO TORELLI, OF NEW HAVEN, CONNECTICUT.

TAILOR'S PIN.

Application filed June 30, 1928. Serial No. 289,492.

My invention relates to a new and improved tailor's pin, designed and constructed with the object, among other things, of producing a pin for tailors testing work that may be quickly applied without disarranging the cloth, will not injure the fingers, and can be manufactured and sold at the minimum cost.

To these, and other ends, my invention consists in the tailor's pin, having such details of construction as are hereinafter described and more particularly pointed out in the claims.

Referring to the drawings, in which like numerals of reference designate like parts in the several figures;

Figure 1 is a front view of my improved pin;

Figure 2 is a side view thereof; and

Figure 3 is a view illustrating the pin being applied to a piece of cloth.

This pin is constructed with a leg member 10, having a pointed end 11 and slightly curved lengthwise, a guide bar 12 substantially parallel with the leg member but much shorter in length terminating at one end in a finger loop 13, and connected at the opposite end with the leg member 10 by the head portion 14. This entire pin is made of a single piece of wire, and is placed in the cloth by grasping the finger loop 13 between the thumb and second finger to guide and weave the leg member therethrough, the operation being assisted by the first finger, which presses against the head portion 14.

In Figure 3 I have illustrated the relative position of the fingers just described. With the common type of pin the body thereof is straight and has a comparatively small head

upon the end thereof, is difficult to insert on account of the straight body, and the size of the head is such that before many pins are inserted the end of the finger becomes tender and sore. With this pin the curved leg readily enters the cloth, designated 15, and it is applied with great ease and without liability of injury to the fingers because the pressure is applied to a head of very large area.

The head portion 14 also serves as a stop of substantial size to prevent the cloth being damaged by too great pressure upon the pin after it has been projected into the cloth its full length.

Having described my invention, what I claim as new and desire to secure by Letters Patent, is:

1. A pin constructed of a single piece of wire, having a curved leg pointed at one end; a guide bar substantially parallel with and joined to the leg by an intermediate head portion upon one side thereof that lies at substantially a right angle to the leg and guide bar; and a finger loop upon the end of the guide bar.

2. A pin constructed of a single piece of wire, having a curved leg pointed at one end; a guide bar substantially parallel with and shorter than the leg member; a finger loop at one end of the guide bar; and a head portion connecting the leg and guide bar, the head portion being at substantially a right angle thereto and projecting laterally upon one side thereof.

In testimony whereof, I have hereunto affixed my signature.

PIETRO TORELLI.
